CLAIM

(21) Appl. No.: **29/528,673**

I claim the ornamental design for the firearm receiver having skull design, as shown and described.

(22) Filed: **May 29, 2015**

DESCRIPTION

(51) **LOC (10) Cl.** **22-01**

FIG. 1 is a perspective view of the firearm receiver having skull design, showing my new design.

(52) **U.S. Cl.**

FIG. 2 is a front view of the firearm receiver having skull design.

USPC **D22/108**

FIG. 3 is a back view of the firearm receiver having skull design.

(58) **Field of Classification Search**

FIG. 4 is a left side view of the firearm receiver having skull design.

USPC D22/103, 108; D21/572-575

FIG. 5 is a right side view of the firearm receiver having skull design.

CPC F41C 23/10; F41C 23/14; F41C 23/16;

FIG. 6 is a top view of the firearm receiver having skull design; and,

F41C 23/18; F41C 23/00; F41C 27/00;

FIG. 7 is a bottom view of the firearm receiver having skull design.

F41C 27/06; F41A 5/18; F41A 5/24; F41A

Aspects illustrated in broken lines in each of the figures form

21/28

no part of the claimed invention.

See application file for complete search history.
